UNITED STATES PATENT OFFICE.

ADRIEN OULLIÉ, OF PARIS, FRANCE, ASSIGNOR TO HIMSELF AND ISIDORE LAMBERT, OF PARIS, FRANCE.

NON-REFILLABLE BOTTLE.

SPECIFICATION forming part of Letters Patent No. 757,955, dated April 19, 1904.

Application filed September 14, 1903. Serial No. 178,111. (No model.)

To all whom it may concern:

Be it known that I, ADRIEN OULLIÉ, chemist, of 83 Rue Blanche, in the city of Paris, Republic of France, have invented Improvements Relating to Non-Refillable Bottles, of which the following is a full, clear, and exact description.

This invention has reference to non-refillable bottles; and it consists of a system of plugs 10 or obturators for preventing bottles carrying good marks or labels from being fraudulently filled with a view to deceive the consumer as to the origin of the liquid contained in the bottle.

15 This invention will be well understood by the aid of the following description and on reference to the accompanying drawings, wherein—

Figure 1 shows the apparatus in external 20 elevation and placed in the neck of any bottle. Fig. 2 shows the same apparatus in vertical section. Fig. 3 shows the apparatus in the position taken up by the parts to permit of the flow of the liquid contained in the bottle. 25 Figs. 4, 5, 6, 7, and 8 show the various parts of the device.

In the various figures the same reference-letters are used to describe the same parts.

According to this invention my improved 30 device consists of a float *a*, formed of a glass ball, of a collar *b*, of another ball *c*, and of a hollow shaft *d*, fitted with wings *e* and containing small shot in the interior. The ball *c* is preferably ground to enable it to apply itself 35 exactly to the lower conical portion of a central sleeve *f*. Above these wings *e* there is another series of wings *g*, incorporated with a rod *h*, a ball *i*, containing small shot, and a rod *j*. This ball is also ground to enable it to exactly 40 fit the upper part of the tube *f*, which is slightly conical for this purpose. The collar *b* engages with a hole *k*, made in the lower portion of a lantern *l* in two parts, with which the sleeve *f* is engaged. The stem *j* of the ball *i* also fits into a hole *m*, formed in the upper 45 portion of the lantern *l*, openings *n* being provided in this latter to admit of the exit of the liquid. Above the rod *j* there is a hole

lled wooden washer *o* and then a very weak spring *p*, preferably of silvered steel, sur- 50 mounted by another wooden washer *q*. Finally, above the washer *q* there is a baffle-plate *r*.

The neck of the bottle is provided with a hood *s*, fixed by means of a suitable cement 55 and into which an ordinary cork or stopper is inserted.

The method of operation of this apparatus is as follows: The bottle being full, a slight shake being given to it, while inclining it at the 60 same time, causes the stem *j* of the ball *i* to fall on the spring *p* and leave the passage open. In this position the ball *c* closes the lower extremity of the sleeve *f*; but the float *a*, raised by the liquid, carries the ball *c* with it, and 65 the liquid flows off normally. When the bottle is empty, the float, being no longer raised, does not carry the ball *c* along with it, which hermetically closes the sleeve when the bottle is inverted. 70

The object of the spring *p* is to influence the ball *i* in the horizontal position, so that whatsoever may be the position given to the bottle no liquid can be introduced into the bottle, so that it cannot be refilled either by 75 vacuum or by pressure or by capillarity. The baffle-plate *r* prevents the penetration of any foreign body which could raise the ball *i*.

The forms, details, accessories, materials, and dimensions of this apparatus can of course 80 be varied without in any way changing the principle of this invention.

I claim—

1. Means for preventing bottles from being fraudulently filled, comprising a discharge-sleeve *f*, two independent balls *c*, *i*, for closing the sleeve, the ball *c* being provided with a float *a* and wings *e* and the ball *i* with wings *g*, a lantern *l* inclosing the sleeve and balls, an abutment-spring *p* above the lantern, a 85 baffle-plate *r* above the spring, and a hood *s* adapted to be secured to the bottle-neck, as described.

2. In a non-refillable bottle, the combination of a bottle having a valve-seat in the neck 95 thereof, a valve arranged to close said seat by

gravity when the bottle is inverted, and a float attached to said valve and extending into the bottle.

3. A non-refillable bottle, the combination 5 of a valve-seat arranged in the neck of the bottle, a valve arranged to engage said seat and close the same by gravity when the bottle is inverted, a float attached to said valve and projecting into the bottle, and means for 10 limiting the movement of the valve and float away from the valve-seat.

4. In a non-refillable bottle, the combination 15 of a valve-seat arranged in the neck of the bottle, a valve arranged to close said seat by gravity when the bottle is inverted, a float attached to said valve and extending into the bottle, a check-valve arranged in the neck of the bottle between said valve and the top of the bottle, and a valve-seat in said neck arranged 20 to be engaged by said valve by gravity, when the bottle is in an upright position.

5. In a non-refillable bottle, the combination 25 of a valve-seat arranged in the neck of the bottle, a valve arranged to close said seat by gravity when the bottle is inverted, a float attached to said valve and extending into the bottle, a check-valve arranged in the neck of the bottle between said valve and the top of

the bottle, a valve-seat in said neck arranged to be engaged by said valve by gravity, when 30 the bottle is in an upright position, and means for limiting the movement of the second valve away from its valve-seat when the bottle is inverted.

6. In a non-refillable bottle, the combination 35 of a valve-seat arranged in the neck of the bottle, a valve arranged to close said seat by gravity when the bottle is inverted, a float attached to said valve and extending into the bottle, a check-valve arranged in the neck of 40 the bottle between said valve and the top of the bottle, a valve-seat in said neck arranged to be engaged by said valve by gravity when the bottle is in an upright position, and a spring above said second valve and arranged 45 to retain the valve seated when in an upright position, but to admit of the valve moving away from its seat by gravity, when the bottle is in an inverted position.

The foregoing specification of my improvements relating to non-refillable bottles signed by me this 29th day of August, 1903.

ADRIEN OULLIÉ.
